UNITED STATES PATENT OFFICE.

AUGUSTA MERIEL MELVILLE-HAMILTON, OF MEDINDIE, SOUTH AUSTRALIA,
AUSTRALIA.

WATER-BOTTLE OR WATER-BAG.

1,019,171.

Specification of Letters Patent.

Patented Mar. 5, 1912.

Application filed September 10, 1910. Serial No. 581,400.

To all whom it may concern:

Be it known that I, AUGUSTA MERIEL MELVILLE-HAMILTON, a subject of the King of Great Britain, residing at Robe Terrace, 5 Medindie, State of South Australia, in the Commonwealth of Australia, have invented certain new and useful Improvements in or Relating to Water-Bottles or Water-Bags, of which the following is a specification.

10 This invention relates to water-bottles or water-bags, particularly adapted for military purposes.

Heretofore, water bottles have usually comprised merely a receptacle of suitable 15 shape and material provided with an orifice or a nozzle for drinking and filling purposes, the said orifice being closed by a cork or plug. During military campaigns or maneuvers such water bottles are frequently filled

20 from any available source regardless of its character or quality; the results of drinking water from indiscriminate sources are too well known to need further statement. Further disadvantages of the water bottles here-

25 tofore in use have also presented themselves, in that it is somewhat inconvenient to drink from the same without wasting the contents, either by spilling, or by unavoidably taking more than is required into the mouth. Fur-

30 thermore, when a soldier for instance is in a prone position it sometimes becomes a matter of considerable inconvenience if not difficulty to raise the bottle to a position from which the contents can be obtained. It also 35 requires some skill to completely empty the bottle owing to the nature and position of the outlet orifice or nozzle.

The present invention has for its chief object to overcome the dangers of obtaining 40 water in the manner hereinbefore referred to by providing the bottles with means for filtering the water contained therein.

A further object is to construct the water-bottle in such a manner as to afford ready 45 means of inspection so that the interior may be kept perfectly clean and also to render the construction of such a character that any desired quantity of the contents can at all times be consumed without waste, while permitting the same to be readily obtained from 50 all positions of the consumer and the entire

contents to be exhausted so that the bottle may be completely refilled with fresh water as often as possible.

According to this invention, the bottle or 55 container is fitted with a filter comprising a suitably shaped hollow block of any appropriate material inclosed in a metallic casing preferably of cylindrical form and having perforations in the inner end of same. The 60 filter is adapted for being carried by the mouthpiece which is provided with a tube so arranged as to enter the hollow filter block. The said tube extends toward the bottom of 65 the filter; the arrangement being such that all water in the bottle must pass to the consumer, through the filter block and the tube, so that all the water is filtered before it is consumed. Furthermore, the provision of 70 the long tube enables the liquid to be readily and comfortably obtained no matter in what position the consumer may be. In certain cases the filter may be dispensed with in which case the contents of the bottle are consumed directly through the aforesaid tube. 75

In order that the said invention may be clearly understood and readily carried into effect, I will proceed to describe the same more fully with reference to the accompanying drawings, in which:— 80

Figure 1 is a view partly in elevation and partly in section illustrating a water bottle embodying the features of the present invention. Fig. 2 is a similar view illustrating the modified form of the bottle hereinbefore referred to. 85

The bottle or bag A is provided with an opening or aperture a which approximately occupies the full width of the bottle. The aperture may be disposed as shown toward 90 one end of the bottle or it may be arranged in any position between the two ends of the bottle. The said aperture is adapted for being closed by means of a screw or other suitable cap such as b the annular wall or 95 stem b' of which is screw-threaded both internally and externally. The external thread engages in an internal thread in a ring c around the aforesaid opening or aperture a. The internal thread in the ring part b' engages with a screw thread on the casing d of 100 the filter e. Washers of leather or other suit-

able or yielding material may be provided between the adjacent surfaces of the cap *b* and the bottle or where necessary.

Projecting from the outside of the screw 5 cap *b* is a tubular nozzle, having a removable cover *g* attached preferably by a bayonet joint. The removable cover *g* is retained from loss when removed from the nozzle by means of a chain connection as shown. The 10 hole through the nozzle is screw threaded for the reception of the end of the tube *h* which is secured in the said nozzle and extends almost to the bottom of the interior or cup of the filter block.

15 A passage *i* is provided in the cap *b* to serve as an air vent to the body of the bottle, as water is withdrawn therefrom. The said passage *i* is normally closed by means of a wing or projection *j* which may 20 form part of the cover *g* or the passage may be closed by means of a separate plug.

The filter block *e* rests upon the bottom of the casing *d* and is formed with a flange *k* at the top so as to close the annulus between the block and the case *d*. The latter extends toward the bottom of the bottle, leaving sufficient space for water to enter between the perforations *l* and the bottom of the bottle. The water enters the 30 casing *d* through these perforations and thence filters through the block *e* into the interior space or cup from whence it can be withdrawn through the tube *h*. The filter block *e* is of such a length as to have 35 the top flush with the top of the casing *d* and a ring or washer *m* of any suitable substance is provided so as to insure a perfect closure of the annular chamber. The casing *d* with the filter *e* and the tube *h* may 40 be readily removed for cleaning purposes as will be apparent from the drawings.

If it is desired to prevent tampering with the internal parts of the chamber *d* the latter may be arranged as an integral part 45 of the cap *b*, the filter block being previously inserted therein, while the tube *h* may be fitted therein so as to permit of the outward withdrawal of the same. Such construction is obvious and needs no special 50 illustration.

In Fig. 2, the filter is dispensed with and the bottle remains with the advantages of the long tube *h* for facilitating drinking without having to tilt the bottle or assume 55 awkward and uncomfortable positions for drinking. The filling orifice may be arranged centrally or toward one side or end and is screw threaded for the reception of a plug or stopper in which the aforesaid 60 tube *h* is mounted so as to project into the bottle approximately to or near the bottom thereof. The plug and orifice are of some-what large diameter so that a large filling 65 aperture is provided. The tube *h* may be detachably mounted in the lug or stopper

or the said tube may be formed integrally with the said plug. If the parts be made separable the cleaning operation is facilitated.

Owing to the fact that the filter is considerably larger than the suction tube, and incloses the same so as to form a chamber in which the filtered liquid will accumulate, and owing to the further fact that the tube has an inlet opening only at its lower end to communicate with said chamber, a sufficient quantity of water for an ordinary drink may be readily obtained without inverting the bottle, and without having to exert any great or special force of suction. 70

The water-bottle or bag may obviously be made of canvas, leather or other similar impervious material and may also be provided with any suitable arrangement of strapping for attachment to the person, or to the saddle or harness or for ambulance use. 75

What I claim and desire to secure by Letters Patent of the United States is:—

1. A water bottle having a filter, and a suction tube within the filter, the relative sizes of the filter and tube being such as to form a chamber for the accumulation of filtered liquid, said tube communicating with said chamber only near the bottom thereof, whereby the accumulation of filtered liquid may be removed by suction. 90

2. A water bottle comprising a body portion having a large filling aperture, a removable cover having a depending wall engaging with said filling aperture, an air vent being provided in said cover, a nozzle on said cover, a cap for closing said air vent and nozzle, and a continuous suction tube connected to said nozzle and extending approximately to the bottom of the water space of the bottle, said tube having an inlet opening only at its lower end. 100

3. A water bottle comprising a body portion, a large filling aperture in said body portion, a removable cover having a depending wall engaging with said filling aperture, a nozzle on said covering, a perforated casing screwed to said cover and a filter tube arranged within said perforated 110 casing for filtering the water passing through the nozzle.

4. A water bottle comprising a body portion having a large filling aperture, a removable cover having a depending wall engaging with said filling aperture, an air vent being provided in said cover, a nozzle on said cover, a cap for closing said air vent and nozzle, a perforated casing screwed to said nozzle, a filter tube arranged within 120 said perforated casing and a tube arranged within said filter tube and extending to the bottom thereof. 125

5. A water bottle comprising a body portion having a large filling aperture, a re- 130

movable cover having a depending wall engaging with said filling aperture, an air vent being provided in said cover, a nozzle on said cover, a cap adapted to close said air vent and secured to the nozzle by a bayonet joint, a perforated casing detachably screwed to said nozzle, a filter tube arranged within said perforated casing and

a tube arranged within said filter tube and extending to the bottom thereof. 10

In testimony whereof I affix my signature in presence of two witnesses.

AUGUSTA MERIEL MELVILLE-HAMILTON.
